6 Claims. (Cl. 8—34)

ABSTRACT OF THE DISCLOSURE

The invention is vat dyeing with a polyamide made from a water soluble condensate of N-aminoethyl piperazine and adipic acid. Other diamines and dibasic acids are also shown. The amide can be quaternized with dimethyl sulfate, ethylene chlorohydrin, glycolchlorohydrin or chloroacetic acid.

The present invention relates to a process for the production of level vat dyeings, wherein polyamides are allowed to act on the fibrous material either during or after dyeing with vat dyestuffs, the said polyamides consisting mainly of:

(a) Structural elements of polyamides that contain at least one tertiary or quaternary nitrogen atom and at least two nitrogen atoms bound to hydrogen, and

(b) Structural elements of dicarboxylic acids.

The polyamides can be prepared in the usual manner by polycondensation of the polyamines defined under (a) with dicarboxylic acids. The said polyamines contain at least three nitrogen atoms, of which at least one must be a tertiary or quaternary atom. In general, it is advantageous to start with polyamines having tertiary nitrogen atoms and then to quaternize the polyamide, so far as a levelling agent with quaternary nitrogen atoms is desired. It is advantageous to choose aliphatic polyamides, or polyamides which, in addition to another radical, for example, an alicyclic or heterocyclic radical, contain at least one alkylene radical.

There are used, for example, polyamines of the formula

in which one of the nitrogen atoms is a tertiary atom, m and n each represent a whole number of a value not higher than 2, and R_1 , R_2 and R_3 represent aliphatic radicals, or two such radicals together with an

$>\text{N-alkylene-N}<$

group may form a heterocyclic ring. Preference is given to derivatives of dipropyletriamine, that is to say, polyamines of the Formula 1 whose

$>\text{N-alkylene-N-alkylene-N}<$

radical has the formula

There may also be used derivatives of triethylene tetraamine. The dialkylene triamines of the Formula 1 contain one ($m=1$; $n=1$) to three ($m=2$; $n=2$) aliphatic substituents, for example, cyano-alkyl radicals, such as cyano-ethyl, or advantageously alkyl radicals, such as methyl, ethyl, isopropyl and n-butyl. The substituents R_1 ,

2

R_2 and R_3 can be identical or different from one another.

Two such substituents can also be joined together so that, together with an $>\text{N-alkylene-N}<$ group, they form a heterocyclic ring

5

as is the case, for example, with N-amino-ethyl-piperazine

10

15

The polyamines are advantageously condensed with aliphatic dicarboxylic acids. There are used for this purpose more especially the simple aliphatic acids that contain at least 5 carbon atoms and that have the formula

20

and more especially those of the formula

25

in which k represents a whole number of a value of at least 3, but preferably not more than 8. Examples are glutaric acid, suberic acid, azelaic acid, sebatic acid and especially adipic acid.

30

As starting materials for certain polyamides of the constitution defined above there can also be used polyamines such as the dialkyleneetriamine of the formula

35

35

that do not contain a tertiary nitrogen atom, the secondary basic nitrogen atoms present being converted into tertiary atoms after polycondensation, for example, with the aid of alkylating or hydroxyalkylating agents, such as dimethyl sulfate or ethylenechlorohydrin. As already mentioned, the procedure can be taken a step further and the tertiary nitrogen atoms quaternized, for example, with the agents just mentioned.

40

The polyamides can be manufactured by a method in itself known, advantageously by heating the two reaction components in a molecular ratio of 1:1, if necessary in the presence of inert solvents and/or agents that split off water, such as toluene sulfonic acid. It is of advantage to work in such a manner that only a low degree of condensation is achieved. Thus, in the reaction of 1 mol of a dicarboxylic acid with 1 mol of polyamine, the amount of reaction water should be at least 20 cc., advantageously about 25 cc. This corresponds to an average degree of condensation of 2, that is to say, the linkage of 2 dicarboxylic acid molecules with 2 polyamine molecules. If condensation is taken further until approximately 29 cc. of water are split off, which corresponds to an average linkage of 3 dicarboxylic acid molecules with 3 polyamine molecules, the levelling action is generally not improved, but remains approximately the same.

45

Some polyamides of the constitution defined above are known. These polyamides are new that consist principally of

50

(a) Structural elements of polyamines that contain at least one tertiary or quaternary nitrogen atom and at least two nitrogen atoms bound to hydrogen of which at most one is a primary nitrogen atom, and

55

(b) Structural elements of dicarboxylic acids, advantageously aliphatic dicarboxylic acids. Of these new polyamides there are specially mentioned those which contain structural elements of polyamines of the formula

60

65

70

in which at least one of the nitrogen atoms is a tertiary atom, n represents a whole number of a value not greater than 2, and R_1 , R_2 and R_3 represent aliphatic radicals, whereby two such radicals, together with an

group, can also form a heterocyclic ring. The alkylene groups are for example, n-propylene groups or advantageously ethylene groups.

Also in the case of the new polyamides there are primarily used as structural elements of dicarboxylic acids, those which have already been mentioned above as being specially valuable.

In accordance with the invention, the polyamides of the aforesaid constitution are used as levelling agents for vat dyeings. They are specially suitable for cellulosic fibers and can be used in all cases where the dyestuff used and/or the material dyed are expected to give rise to unlevel dyeings or have already given rise to unlevel dyeing. For example, the polyamides can be added to the dyebaths so that they exert a levelling action during the dyeing process. On the other hand, unlevel vat dyeings can subsequently be levelled up with the assistance of the polyamides in an alkaline bath that contains hydrosulfite. The quantity of polyamide that can be added to the treatment baths can vary between fairly wide limits; the quantity used is advantageously 0.25 to 5 parts of polyamide per 1000 parts by volume of water.

Unless otherwise stated, the parts and percentages in the following examples are by weight, and the temperatures are given in degrees centigrade.

Example 1

A dyebath is prepared from 1000 parts of water, 16 parts of sodium hydroxide solution of 30% strength, 2 parts of sodium hydrosulfite, 0.1 part of the dyestuff of the formula

and 1 part of a 50% solution of a polyamide, the manufacture of which is described below. 100 parts of cotton yarn on cheeses are dyed for one hour at 50 to 60° C. in the bath so prepared. The dyeings are then oxidised and finished in the usual manner. The yarn on the cheeses is dyed violet and is very well penetrated by the dyestuff, which is in contrast to a dyeing carried out in the same manner but without the addition of the polyamide.

The polyamide is manufactured as follows: A reaction mixture consisting of 146 parts of adipic acid (1 mol), 126 parts of N-amino-ethylpiperazine of Formula 3 (1 mol), 1.5 parts of para-toluene-sulfonic acid and 500 parts of xylene is allowed to boil for 15 hours while a current of nitrogen is passed through it, and the water that is formed is continually removed with the assistance of a suitable separator. After this period, there are about 25 parts of water in the separator. The xylene is then distilled off in vacuo. A highly viscous mass remains which is dissolved in the same amount by weight of water, thus giving a 50% solution of the polyamide.

In place of this polyamide, when dyeing according to the instructions given in the first paragraph of this example, a polyamide can be used that is obtained by maintaining the aforesaid reaction components at 160 to 165° C. for about 7 hours, without a solvent and with a descending condenser until 29 parts of water have collected

in the receiver which is cooled with ice, and then dissolving the reaction product so obtained in water in the same manner.

A good levelling action is also obtained with the following dyestuffs just as well as with the dyestuff of the Formula 8

black

Example 2

The same procedure is adopted as described in Example 1, but one of the polyamides described below under A, B and C is used. A levelling action is likewise obtained.

(A) 146 parts of adipic acid (1 mol), 208 parts of the compound of the Formula 6 (1 mol), which is obtained by the additive combination of 2 molecules of acrylonitrile with 1 molecule of diethylene-triamine, and 1.5 parts of para-toluene-sulfonic acid are heated to 160° C. in a reaction vessel equipped with a stirrer and descending condenser. The mixture becomes viscous after $\frac{3}{4}$ to 1 hour, but can still be stirred easily. The mixture is cooled to 140° C., 10 parts of ethylene glycol are added,

and the mixture is further cooled to 120° C. The descending condenser is then replaced by a reflux condenser, whereupon 126 parts of dimethylsulfate (1 mol) are slowly added dropwise, and the mixture is maintained at 120 to 130° C. for a further 1 to 2 hours. The heating bath is then removed, and 240 parts of water are slowly added, the said water being immediately taken up by the reaction product. After cooling there are obtained about 694 parts of a solution with a polyamide content of about 50%.

(B) 146 parts of adipic acid (1 mol), 126 parts of amino-ethylpiperazine of the Formula 3 (1 mol) and 1.5 parts of para-toluenesulfonic acid are maintained at 160 to 165° C. for 3 to 4 hours in a reaction vessel with a descending condenser while stirring. After this period, there are 26 parts of water in the receiver, which is cooled with ice. The reaction mixture is then cooled to 130 to 140° C. and, after the addition of 20 parts of ethylene glycol, it is cooled to 120° C. 126 parts of dimethyl sulfate (1 mol) are then allowed to run in slowly at that temperature, and stirring is continued for a further 2 hours at 120 to 130° C. 120 parts of water are then added. After cooling, there are obtained about 504 parts of a clear, viscous solution that contains about 50% of polyamide.

(C) 132 parts of glutaric acid (1 mol), 126 parts of amino-ethylpiperazine of the Formula 3 (1 mol) and 1.5 parts of para-toluenesulfonic acid are maintained at about 160° C. for 4 hours in a reaction vessel with a descending condenser while stirring. The reaction mixture is then allowed to cool to 140° C., whereupon 20 parts of ethylene glycol are added, and the mixture is allowed to cool further to 130° C. After 210 parts of water have been added and the mixture has cooled to room temperature, there is obtained a clear, viscous solution (460 parts) that contains about 50% of polyamide.

Example 3

An unlevel dyeing on cotton tricot produced with 0.5% of the green dyestuff of the formula

is treated for 1 hour at 60° C. in a goods-to-liquor ratio of 1:30 in an aqueous bath that contains, per 1000 parts of water, 16 parts of sodium hydroxide solution of 30% strength, 3 parts of sodium hydrosulfite and 2 parts of the polyamide solution described below. The unlevelness disappears completely after re-oxidation has been carried out in the usual manner.

The polyamide is manufactured as follows: A mixture of 146 parts of adipic acid (1 mol), 145 parts of N-methyl-bis-N-3-amino-propylamine of the formula

(1 mol), 1.5 parts of para-toluenesulfonic acid and 500 parts of xylene is maintained at the boil for 20 hours while a current of nitrogen is passed through, and the water that is formed is continually removed with the aid of a suitable separator. After this period, there are about 20 parts of water in the separator. Xylene is distilled away from the polyamide so formed, which is insoluble in xylene, and the residue is maintained at about 160° C. for 5 hours under a reduced pressure of about 50 mm. Hg. The viscous product so obtained is then dissolved in the same amount by weight (about 250 parts) of water.

An unlevel dyeing produced with the blue dyestuff of the Formula 9 can also be levelled up in the same manner.

50 (16)

65 likewise in the form of a finely dispersed powder, and, as levelling agent, there is used 0.8 part of one of the preparations G or H described below. The dyeings obtained are level.

The preparations G and H are prepared in the following manner:

(G) 146 parts of adipic acid (1 mol), 126 parts of N-amino-ethyl-piperazine (1 mol) and 1.5 parts of para-toluenesulfonic acid are maintained at 160 to 165° C. for 3 to 4 hours in a reaction vessel with a descending condenser until 26 parts of water have collected in the re-

Example 4

10 parts of cotton satin are dyed for 1 hour at 60° C. in a dyebath prepared from 800 parts of water, 13 parts by volume of a sodium hydroxide solution of 30% strength, 1.6 parts of sodium hydrosulfite, 0.3 part of a concentrated aqueous paste of a dyestuff that is obtained from methyl benzanthrone by sulfur fusion, and 0.8 part of one of the preparations described below under D, E or F. The dyeing is then oxidized and finished in the usual manner. A level blue dyeing is obtained.

The preparations mentioned above are obtained in the following manner:

(D) 174 parts of suberic acid (1 mol), 126 parts of N-amino-ethyl-piperazine (1 mol) and 1.5 parts of para-toluenesulfonic acid are maintained at 160 to 165° C. for 4 to 5 hours in a reaction vessel with a descending condenser while stirring. After the reaction mixture has cooled to 140° C., 10 parts of ethylene glycol are added, after which 260 parts of water are added, when the reaction mixture has cooled to 130° C.

There is obtained a clear, viscous solution that contains about 50% of polyamide.

(E) 188 parts of azelaic acid (1 mol) and 126 parts of N-amino-ethyl-piperazine (1 mol) are reacted in the presence of 1.5 parts of para-toluenesulfonic acid in the same manner as in the manufacture of preparation D. 26 parts of water collect in the receiver. 10 parts of ethylene glycol are added at 140° C., and then 275 parts of water are added at 130° C., whereupon a clear solution is obtained.

(F) 202 parts of sebacic acid (1 mol), 252 parts (1 mol) of the reaction product of 1 part of triethylene-tetramine and 2 moles of acrylonitrile and 1.5 parts of para-toluenesulfonic acid are maintained at 160° C. with a descending condenser while stirring until the reaction mixture becomes viscous, but is still easily stirred. 252 parts of dimethyl sulfate (2 mols) are added dropwise at 140 to 150° C., and the reaction mixture is then maintained at 120 to 130° C. for 2 hours. After dissolving in 240 parts of water there is obtained a preparation that contains about 50% of polyamide.

Example 5

45 Dyeing is carried out by the method described in Example 4, but there is used 0.05 part of a dyestuff (obtained by the alkaline fusion of benzanthrone with subsequent bromination) in the form of a finely dispersed powder, or 0.05 part of the dyestuff of the formula

50

55

60

65

70

75

ceiver. The reaction mixture is then allowed to cool to 130° C., whereupon 247 parts of butylene glycol are added, in which the reaction mixture dissolves.

After cooling, there are obtained 492 parts of a paste that contains 50% of polyamide (preparation G₁).

49.2 parts (1 mol) of the preparation G₁ so obtained are heated to 100° C. in a vessel equipped with stirrer and reflux condenser, and 8.8 parts (1.1 mol) of glycolchlorohydrin are then added dropwise. The reaction mixture is maintained at 110 to 115° C. for 6 hours. There is obtained a preparation of which a considerable proportion comprises the quaternation product of the polyamide used.

(H) 49.2 parts (1 mol) of the preparation G₁ described in the manufacture of preparation G are quaternated with 10 parts (1.05 mol) of chloracetic acid amide for 4 hours at 60 to 65° C. and then for 2 hours at 90 to 95° C.

What is claimed is:

1. A process for the production of level vat dyeings, which comprises applying to the fibrous material in combination with the vat dyestuff as a levelling agent a low molecular polyamide obtained from condensation of (a) about 1 mol of a polyamine of the formula

and of (b) about 1 mol of a dicarboxylic acid of the formula HOOC—(CH₂)_k—COOH in which k represents a whole number of at least 3 and at the most 8.

2. A process for the production of level vat dyeings, which comprises applying to the fibrous material in combination with the vat dyestuff as a levelling agent a low molecular polyamide obtained from condensation of (a) about 1 mol of a polyamine of the formula

and of (b) about 1 mol of adipic acid.

3. A process for the production of level vat dyeings, which comprises applying to the fibrous material in combination with the vat dyestuff as a levelling agent a low molecular polyamide obtained from condensation of (a) about 1 mol of a polyamine of the formula

and of (b) about 1 mol of adipic acid, the average condensation degree being at least 2 and at most 3.

4. A process for the production of level vat dyeings, which comprises applying to the fibrous material in com-

bination with the vat dyestuff as a levelling agent the quaternary ammonium compound from dimethyl sulfate and a low molecular polyamide obtained from condensation of (a) about 1 mol of a polyamine of the formula

and of (b) about 1 mol of adipic acid.

5. A process for the production of level vat dyeings, which comprises applying to the fibrous material in combination with the vat dyestuff as a levelling agent the quaternary ammonium compound from glycolchlorohydrin and a low molecular polyamide obtained from condensation of (a) about 1 mol of a polyamine of the formula

and of (b) about 1 mol of adipic acid.

6. A process for the production of level vat dyeings, which comprises applying to the fibrous material in combination with the vat dyestuff as a levelling agent the quaternary ammonium compound from chloracetic acid amide and a low molecular polyamide obtained from condensation of (a) about 1 mol of a polyamine of the formula

and of (b) about 1 mol of adipic acid.
